UNITED STATES PATENT OFFICE.

MORRIS MOSKOWITZ, OF NEWARK, NEW JERSEY, ASSIGNOR TO THE NATIONAL ELECTRIC CAR LIGHTING COMPANY, OF WEST VIRGINIA.

DESIGN FOR A CASING FOR DYNAMOS.

SPECIFICATION forming part of Design No. 25,529, dated May 19, 1896.

Application filed January 11, 1896. Serial No. 575,185. Term of patent 14 years.

To all whom it may concern:

Be it known that I, MORRIS MOSKOWITZ, a citizen of the United States, residing at Newark, in the county of Essex and State of New Jersey, have invented a certain new and useful Design for a Casing for Dynamos; and I do hereby declare the following to be a full, clear, and exact description of the same, such as will enable others skilled in the art to 5 to which it pertains to make and use it, reference being had to the accompanying drawings, which form part of this specification.

My invention relates to a new and useful design for a casing for dynamos such as is 10 used on the axles of railway-cars, from which the dynamo derives its power to generate electricity; and it consists in the novel configuration and ornamentation of the casing shown.

The design is clearly illustrated in the accompanying drawings, in which—

Figure 1 is a perspective view of my novel design for a casing when looking at the same from the top, and Fig. 1^a is a similar view of the casing when the same is viewed from the 15 bottom. Figs. 2 and 3 are two vertical cross-sections of the casing, said sections being represented as taken in planes at right angles to each other.

The casing herein shown is to be used in 20 connection with a dynamo placed on one of the axles of a railway-car.

In said drawings, A indicates my novel form of casing, the body of which has a flat top a, which is formed with the curved edge a' surrounding it on its four sides. The downwardly-extending sides are connected by the 25 curved corners a², and each side has a ledge a³, which projects at a right angle from the body of the casing. Said ledge has the round-

ed corners a⁴ and on the two opposite sides 40 is relieved by semicircular portions a⁵, which are open, as at a⁶, and when viewed in side elevation form semicircles, as clearly represented in Fig. 2. Depending from the inner surface of the top of the casing is a projection b, which is of a rectangular shape, but is formed with the rounded edges b' and the lower surface b², which is concavo, being the true arc of a circle when viewed in cross-section. 45

In the top and bottom surfaces of the casing is a depression c, which extends down into said projections b. The four sides of said depression are bounded by the curved edges c', and said sides are inwardly inclined toward 50 the points where they meet the flat surface c² of said depression. The continuity of said ledges a³, as has been stated, is broken on two opposite sides by the curved recesses or open parts a⁶, which are in perfect alinement with 55 each other.

The essential feature of my design is the ornamental feature of the casing, having the marginal ledge a³, which is broken on opposite sides by the curved recesses, and the ornamental projection b, substantially as shown. 60

Having thus described my invention, what I claim is—

The design for a casing for dynamos, substantially as herein shown and described. 70

In testimony that I claim the invention set forth above I have hereunto set my hand this 26th day of December, 1895.

MORRIS MOSKOWITZ.
